TRUE VIBRATO

Selon O. Boyd, Box 2372, El Cajon, Calif.
Filed Feb. 19, 1962, Ser. No. 174,190
9 Claims. (Cl. 84—313)

This invention relates to a vibrato for musical instruments.

The primary object of this invention is to provide a device for controlling the tone of string instruments and to provide an attachment that can be quickly mounted upon and removed from the strings of the instrument.

Another object of the invention is to provide a tone control device which does not require the modification of the instrument or its mutilation, or the use of any fastening means on the sounding board or sounding box, or any other part of the instrument, and which permits the retaining of the original tailpiece.

Another important object of the invention is to provide a tone control device of the type termed as vibrato which is compact, inexpensive and simple so that the same can be placed in use by simple coaction with the strings of the instrument and which can be easily operated at will of the musician while his hands and fingers are in the substantially normal playing position.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

FIG. 1 is a fragmental perspective view of a string musical instrument showing a vibrato made in accordance with the present invention mounted on the strings of the instrument.

FIG. 2 is a cross-sectional view of the vibrato in position on an enlarged scale with respect to FIG. 1 and

FIG. 3 is a partly sectional view of the vibrato looking toward the tailpiece of the instrument from below the bridge.

The tone control device denoted in its entirety by the numeral 1 is shown mounted on a guitar 2. It is to be understood that my tone control device may be used on other types of string musical instruments, such as banjos, ukulele, mandolines and the like. The guitar 2 has a sounding box 3. The uppermost surface of the sounding box 3 which is the equivalent of a sounding board 4 supports a usual bridge 6 under strings 7. The tail ends of the strings 7 are secured in the usual manner to a so called tailpiece 8.

The tailpiece 8 includes an anchor or clamp 9 from which extend wires 11 secured to a cross-bar 12. The wires 11 are secured in a transverse sleeve 13 formed on the anchor or clamp 9.

My tone control device includes a shaft 14 provided with a plurality of passages 16. Each passage 16 is generally diametrical to the shaft 14 and has a countersunk enlarged recess 17 formed at each end thereof. The strings 7, preferably in pairs, are extended through the respective passages 16 in the manner shown in FIG. 2. Each string 7 is extended over the top of the shaft 14 and then it is turned back upon itself and through the

2

passage 16 and then out of said passage 16 from the same side of the shaft 14 nearer the bridge 6 and then under the shaft 14 to the cross-bar 12 in which latter the string 7 is anchored in the usual manner not shown.

5 The shaft is supported in an initial position shown in FIG. 2, wherein the passages 16 are generally parallel with the sounding board 4 and generally at right angles to the bridge 6, by a spring bracket 18. The spring bracket 18 consists of a loop 19 located so that it rests upon the wires 11 of the tailpiece 8 as shown in FIG. 1. A clamp bar 21 extends under the wires 11 and has upwardly extended hooks 22 formed at each end thereof, fitting over the adjacent portions of the spring loop 19, as shown in FIG. 1, so as to hold the spring loop 19 in fixed position relatively to the tailpiece 8.

On each end of the loop 19 the wire is formed into a suitable spring coil 23. From each spring coil 23 extends an end 24 through a hole 26 in the shaft 14, which hole 26 is generally perpendicular and at right angles to the plane in which the string passages 16 lie. A nut 27 with a set screw 28 threaded therein is positioned beneath each end of the shaft near each spring leg 24.

The set screw 28 in the nut 27 is adjusted to bear tightly against the shaft 14 so that as the shaft 14 is rocked by the handle 41, it does not rise or lower relatively to the sounding board 4, but the adjustment is such that it permits the limited rocking of the shaft in opposite directions for the required vibrato.

The spring coils 23 are so set as to hold the shaft 14 in the initial position shown in FIGS. 1 and 2.

One end of the shaft 14 is provided with threads 31. A locknut 32 is threaded on the threads 31 and an internally threaded sleeve 33 is threaded on said threaded portion 31 against the nut 32. The sleeve 33 has transverse threaded holes 34 therethrough into which is secured a bolt 36 in the manner shown in FIG. 3. Spaced from the head of the bolt 36 is a handle locknut 37 and an upwardly dished lock washer 38. The washer 38 is so dished as to nestle therein the wire legs 39 of a handle 41 and thereby permit the handle locknut 37 to tightly clamp the handle in place. The location of the handle 41 with respect to the strings 7 can be adjusted and determined by loosening the locknut 32 and threading the sleeve 34 to the adjusted position and then retightening the locknut 32 to hold the handle 41 in the adjusted position.

The aforementioned simple structure can be easily assembled on existing musical instruments without requiring replacement or reconstruction of any part of the musical instrument. Namely, the strings 7 are drawn through the passages 16 of the shaft 14 in the manner heretofore described. Then the loop 19 is placed in position over the wires 11 of the tailpiece 8 and is clamped in that position by the hooks 22 of the clamp bar 21 which is inserted under the wires 11. The legs 24 of the spring coils 23 are inserted in the perpendicular holes 26 of the shaft 14 and thereby locate the shaft 14 in the initial position, as heretofore described. Finally the initial handle position is adjusted by the sleeve 33 and locknut 32. In order to operate the tone control device, it is only necessary for the player to lift the handle 41 when vibrato is desired, whereby the shaft 14 will be rocked in a clockwise direction viewing FIGS. 1 and 2, exerting corresponding pull on the strings 7 for the effect desired.

65 When the handle 41 is released, the action of the spring coils 23 will cause the shaft 14 to rock back to its initial position as shown in FIGS. 1 and 2. When the handle is thus pulled up away from the instrument the tone played on the string 7 of the instrument is raised in pitch. In order to cause the notes being played to lower in pitch, the player pushes the handle down toward the instrument and the shaft 14 rolls slightly in

contra-clockwise direction viewing FIGS. 1 and 2 releasing the tension of the strings as needed for the lower pitch. These motions repeated about three or six times a second create a true vibrato. The rocking motion required for the vibrato is very slight and can be accomplished positively and with ease.

When the handle 41 is not in use, it can be pushed into an out of the way position and as the handle is turned outwardly into the dotted line position, shown in FIG. 1, it turns the bolt 36. A set screw 42 in the end of the sleeve 33 can be adjusted to regulate the tightness of the bolt 36 in its position for holding the handle 41 against accidental swinging to an out of the way position.

I claim:

1. In tone control device for a string instrument having a tailpiece extended over the face of the instrument and having strings secured to said tailpiece;
  - (a) a rockable member extended transversely of said strings and spaced from said tailpiece
  - (b) said rockable member having passages therethrough
  - (c) said strings being drawn through said passages respectively and then connected to said tailpiece so as to be tightened and loosened by the rocking of said rockable member in respective opposite directions
  - (d) a resiliently yieldable element attached to said tailpiece
  - (e) spring means on said yieldable element to connect it to said rockable member so as to bias it into an initial position
  - (f) and handle means on said rockable member overlying said face of said instrument, whereby said rockable member can be rocked in opposite directions respectively for tightening or loosening said strings for tone control.
2. The tone control device defined in claim 1 and
  - (g) each end of each passage having a smoothly flared countersunk portion to guide the string therethrough.
3. In tone control device for a string instrument having a tailpiece extended over the face of the instrument and having strings secured to said tailpiece;
  - (a) a rockable member extended transversely of said strings and spaced from said tailpiece
  - (b) said rockable member having passages therethrough
  - (c) said strings being drawn through said passages respectively and then connected to said tailpiece so as to be tightened and loosened by the rocking of said rockable member in respective opposite directions
  - (d) a generally U shaped loop attached to said tailpiece
  - (e) a spring coil formed on each leg of said loop and connected to said rockable member so as to bias said rockable member into an initial position
  - (f) and handle means on said rockable member overlying said face of said instrument whereby said rockable member can be rocked in opposite directions from said initial position respectively for tightening and loosening said strings for tone control.
4. The tone control device defined in claim 3 and said handle means including,
  - (g) a sleeve threaded on an end of said rockable member,
  - (h) means to lock said sleeve to said rockable member in adjusted position
  - (i) a manipulable arm secured on said sleeve in an initial position so as to be movable toward and away from said face of said instrument for rocking said rockable member
  - (j) and adjustable pivot means for said arm to permit the turning of said arm away from said rockable member.

5. The tone control device defined in claim 3, and
  - (g) said loop being positioned on top of said tailpiece
  - (h) a clamping element positioned beneath said tailpiece
  - (i) and means on the ends of said clamping element to engage said loop so as to clamp the loop to said tailpiece.
6. In tone control device for a string instrument having a tailpiece extended over the face of the instrument and having strings secured to said tailpiece;
  - (a) a rockable member extended transversely of said strings and spaced from said tailpiece
  - (b) said rockable member having passages therethrough
  - (c) resiliently yieldable means to hold said rockable member spaced from said tailpiece in an initial position
  - (d) said strings being drawn through said passages and then secured to said tailpiece so as to be tightened and loosened by respective opposite rocking of said rockable element
  - (e) and manipulating means on said rockable element for rocking said rockable element at will.
7. In a tone control device for a string instrument having a tailpiece extending over the face of the instrument, and strings secured to said tailpiece,
  - (a) a rocking shaft extended transversely above said face spaced from said tailpiece
  - (b) said shaft having spaced passages therethrough for said strings
  - (c) said strings being drawn through said respective passages and then secured to said tailpiece so as to be tightened and loosened by respective turning of said shaft in opposite directions
  - (d) a clamping loop affixed to said tailpiece
  - (e) resilient means to connect said clamping loop to said shaft so as to bias said shaft to an initial position holding said passages at an initial angle relatively to said tailpiece
  - (f) and manipulable means for turning said shaft from said initial position at will for controlling the tension of said strings.
8. In a tone control device for a string instrument having a tailpiece extending over the face of the instrument, and strings secured to said tailpiece,
  - (a) a rocking shaft extended transversely above said face spaced from said tailpiece
  - (b) said shaft having spaced passages therethrough for said strings
  - (c) said strings being drawn through said respective passages and then secured to said tailpiece so as to be tightened and loosened by respective turning of said shaft in opposite directions
  - (d) a spring loop positioned on top of said tailpiece
  - (e) a clamp element beneath said tailpiece
  - (f) means on said clamp element to engage said loop and affix it to said tailpiece
  - (g) spring coils formed on each end of said loop
  - (h) a leg formed on each spring coil and inserted through said shaft so as to bias said shaft into an initial position
  - (i) and manipulable means for rocking said shaft in opposite directions respectively to tighten and loosen said strings.
9. The tone control device defined in claim 8 and
  - (j) and adjustable spacing means between said instrument face and said shaft to inhibit lowering and raising of said shaft relatively to said face.
